United States Patent Office

Des. 227,685
Patented July 10, 1973

227,685

EDUCATIONAL GAME BOARD

Kenneth A. H. Gordon, Bedford, and Charles L. Chesnut,
Chappaqua, N.Y., assignors to The Reader's Digest
Association, Inc., New Castle, N.Y.

Filed July 3, 1972, Ser. No. 268,779

Term of patent 14 years

Int. Cl. D21—01

U.S. Cl. D34—5 SS

The figure in the drawing forms a plan view of an educational game board, showing our new design.

The design shown in the drawing is of no appreciable thickness.

We claim:

The ornamental design for an educational game board, substantially as shown and described.
